UNITED STATES PATENT OFFICE.

NECHOLAS STEIN, OF PHILADELPHIA, PENNSYLVANIA.

DESIGN FOR A FRAME FOR PICTURES, &c.

SPECIFICATION forming part of Design No. 26,276, dated November 17, 1896.

Application filed October 7, 1896. Serial No. 608,183. Term of patent 7 years.

To all whom it may concern:

Be it known that I, NECHOLAS STEIN, a subject of the Emperor of Russia, and a resident of Philadelphia, Pennsylvania, have invented 5 a certain new and useful Design for Frames, of which the following is a specification.

My design for a frame is fully illustrated in the accompanying drawing, which represents a face view of the frame.

10 The essential feature of the design is the frame having a rampant lion on each side and a spread eagle above.

15 A is the border of the frame. On each side, supporting the sides of the frame, are rampant lions B. Above the border of the frame is an eagle D with wings outspread and having on

its breast a shield d, with arrows on one side and an olive branch on the other. Below the border of the frame is a shell E, having branches extending from each side thereof. 20

I claim—

The design for a frame as described herein and as illustrated in the accompanying drawing.

25 In testimony whereof I have signed my name to this specification in the presence of two subscribing witnesses.

NECHOLAS STEIN.
